UNITED STATES PATENT OFFICE.

FRANK L. HAMILTON, OF FORD CITY, PENNSYLVANIA, ASSIGNOR OF ONE-HALF TO
WILLIAM E. GREGG, OF FORD CITY, PENNSYLVANIA.

SHIPPING-CASE.

1,254,688.

Specification of Letters Patent. Patented Jan. 29, 1918.

Application filed March 3, 1914. Serial No. 822,147.

To all whom it may concern:

Be it known that I, FRANK L. HAMILTON, a citizen of the United States of America, residing at Ford City, in the county of Armstrong and State of Pennsylvania, have invented certain new and useful Improvements in Shipping-Cases, of which the following is a specification, reference being had thereto in the accompanying drawing.

10 This invention relates to shipping cases, more particularly of the braced knock-down class, and has for its object to provide a shipping case particularly adapted for the shipment of plate glass, and which, when set up, 15 presents a rigid structure capable of withstanding rough usage to which it is subjected during transportation, to prevent listing of the case during transportation, and further thoroughly protecting the contents of the 20 case.

A further object of the invention is to provide, in a manner as hereinafter set forth, a shipping case designed primarily for use in the shipment of plate glass, and having 25 the various elements thereof detachably connected together whereby the case can be conveniently knocked down, and the elements constituting the case used again when occasion so requires, providing a great saving in 30 material.

A further object of the invention is to provide a braced plate glass shipping case capable of being assembled and disassembled, and which, when used, will save time in the packing 35 of the glass, loading the case upon a car, unloading the case, and furthermore save time in the unpacking of the case, and also obtain a greater shipment per car than by the method and means now employed for 40 shipping plate glass.

A further object of the invention is to provide a braced shipping case for plate glass whereby greater security is obtained in shipment than is secured by the method and 45 means now employed.

A further object of the invention is to provide a braced shipping case whereby, when employed, the cost of packing, shipping and unpacking will be materially decreased over 50 the means and method now in vogue for packing, shipping and unloading plate glass.

Further objects of the invention are to provide a braced shipping case for plate glass which is comparatively simple in its 55 construction and arrangement, strong, dura-

ble, readily set up and conveniently knocked down, efficient in its use, unusually compact when knocked down, comparatively inexpensive to manufacture, and capable of being employed over and over again for storing and shipping plate glass.

With the foregoing and other objects in view the invention consists of the novel construction, combination and arrangement of parts to be hereinafter more specifically described and illustrated in the accompanying drawings, wherein is shown an embodiment of the invention, but it is to be understood that changes, variations and modifications can be resorted to which come within the scope of the claim hereunto appended.

In describing the invention in detail, reference is had to the accompanying drawings wherein like characters of reference denote corresponding parts throughout the several views, and in which:—

Figure 1 is a perspective view of a braced shipping case in accordance with this invention;

Fig. 2 is an end view thereof; 80
Fig. 3 is a vertical sectional view, broken away;

Fig. 4 is a vertical sectional view;

Fig. 5 is a disassembled view, broken away, and in perspective of certain elements 85 of the case;

Fig. 6 is an end view of a modified form; and

Figs. 7, 8, 9, 10 and 11 are views illustrating details of the form shown in Fig. 6. 90

Referring to Figs. 1 to 5 of the drawings, the body portion of the case consists of a pair of end walls 12—13, side walls 14—15, a bottom 16 and a cover 17.

The side and end walls are formed of metallic plates of the desired thickness and weight and each of said end walls has the top and bottom thereof provided with outwardly projecting lateral flanges 18—19 respectively, and each of the side walls is provided at its top and bottom with outwardly extending lateral flanges 20—21. The flanges 18, 19, 20, 21 are of the same length as the length of their respective walls, and each of said flanges at each end, is formed 100 with a plurality of openings 22, and the openings of the upper flange register with the openings of the lower flange. When the body portion is set up, the side and end walls abut against each other as illustrated in Fig. 110

5, and the said side and end walls are connected together by corner pieces 23 which are angle-shaped, and each of said corner pieces is provided, at its top and bottom, with an outwardly projecting angle-shaped lateral flange, and the legs of each of said flanges are indicated at 24—25, and each of said legs is formed with a plurality of openings 26. The corner pieces are positioned 10 against the outer faces of the side and end walls between the flanges 18—19, and 20—21, and the legs 25 of the flanges of the corner pieces abut against the inner faces of the flanges 20—21, and the legs 24 of the flanges of the corner pieces abut against the inner faces of the flanges 18—19. The openings 26 register with the openings 22 for the purpose of passage of hold-fast devices to be 15 presently referred to. The cover 17 and bottom 16 are formed of a series of wooden bars, or if desired, one piece material, and the said series of bars of the bottom 16, and of the cover 17, are secured together by longitudinally extending cleats 27—28 and 29, or if desired, the cleat 28 can be dispensed 20 with. When the cleat 28 is employed, it is disposed centrally with respect to the cover, or the bottom. The cleat 27, as well as the cleat 29, is arranged inwardly with respect 25 to the longitudinal edge of the cover 17, or the bottom 16.

The bottom 16, and the cover 17, have secured to the outer faces thereof, spaced metallic plates 30, provided with openings 31. Openings 32 are provided in the bottom 16 and cover 17 and the said openings 32 register with the openings 31 in the plates 30. Securing devices 33 are employed for connecting the plates 30 in position.

40 The corners of the cover, as well as the corners of the bottom, project over the space 34 formed at the ends of the flanges 18 to 21 whereby the ends of the flanges are protected.

45 The bottom 16 and cover 17 are provided with openings 35 which register with the openings 22 of the flanges 18 to 21 for a purpose to be presently referred to.

The bottom 16 is detachably secured to 50 the flanges 19 and 21, by headed bolts 36, which extend through the said flanges 19 and 21, and through the openings 35 in the bottom 16, and further through the openings 31, of the plates 30, which are secured to said bottom 16. The bolts 36 project outwardly from the bottom 16 and have mounted thereon nuts 37 which abut against the plates 30. The cleats 27 and 29 act as a protecting medium for the nuts and projecting ends of the bolts in view of the fact that the said cleats are of greater height than the projecting ends of the bolts.

60 The cover 17 is secured to the flanges 18 and 20 through the medium of headed bolts 65 38 which project up through the said flanges,

through the openings 32 in the cover 17 and through the openings 31 in the plates 30 which are secured to the cover 17, and the said projecting ends of the bolts 38 have mounted thereon nuts 39 which abut against the plates 30. The cleats 27—29 of the cover 17 protect the nuts 39 on the projecting ends of the bolts 38.

With the foregoing construction and arrangement of parts it is evident that the body portion of the shipping case is formed of a series of elements detachably secured together, and which permits of the body portion being conveniently knocked down and set up when occasion so requires.

80 The legs 24—25 of the flanges of the corner pieces 23, at the ends of the side wall 15, and one end of the end walls 12—13 are secured to the flanges 18 to 21 by short bolts 40 passing through the openings 22—26 and 85 35, and nuts 41 carried by the bolts 40, and which abut against the bottom 16 and cover 17.

The legs 25 of the flanges of the corner pieces 23, arranged at the end of the side 90 wall 14, are secured to the flanges 20—21 by bolts and nuts corresponding to the bolts and nuts 40 and 41. The bolts pass through the said legs 25, flanges 20—21, and through the cover and bottom, and the nuts abut 95 against the cover and bottom. A part of the bolts extend through the opening 26—22 and 35.

The legs 24 of the flanges of the corner pieces 23 which are arranged at the other 100 end of the end walls 14—15 are secured to the flanges 18—19, bottom 16 and cover 17 by elongated headed bolts 44, and which are provided with nuts 45 abutting against the cover 16. The elongated bolts 44 further constitute means for securing to the body of the case a flanged coupling plate 46^a. The flanges of the plate 46^a are indicated at 47 and abut against those legs 24 of the flanges of the corner pieces 23 through 110 which extend the elongated bolts 44. Each of the coupling plates 46^a is provided with an outwardly extending threaded member 46 for the purpose to be presently referred to.

115 The shipping case further includes extensible and contractible pivoted brace members which maintain the case on edge and which extend in opposite directions with respect to each other, and at their upper ends are connected to the threaded members 46, and at their lower ends are pivotally connected to an anchor. Each of the braces consist of an upper section 47^a, a lower section 48, a turnbuckle 49, a pair of jam nuts 50, and an anchor 51. The upper section 47^a has its lower end peripherally threaded as at 52, and the lower section 48 has its upper end peripherally threaded as at 53. The turnbuckle 49 engages with the peripherally threaded ends 52—53 of the 120 125 130

sections 47^a—48 and one of the jam nuts 50 is mounted upon the threaded portion 52 above the upper end of the turnbuckle, and the other jam nut 50 is mounted upon the 5 threaded portion 53 below the lower end of the turnbuckle 49. The upper end of the section 47^a is flattened as at 54 and formed with an opening for the passage of the threaded member 46, and the said flattened 10 end 54 of the section 47^a, is secured upon the threaded member 46 by a nut 55. The lower end of the section 48 is flattened as at 56, and extends between a pair of vertically disposed lugs 57, carried by a plate 58. Ex- 15 tending through the lugs 57 and the end 56 of the section 48, is a pin 59 for pivotally connecting the lower end of the section 48 to the lugs 57. The plate 58 is provided with openings 60 for the passage of hold-fast de- 20 vices to fixedly secure said plate 58 to a support, by way of example, the floor or wall of the car. The lugs 57, plate 58, and pin 59 constitute an anchoring device for pivotally connecting the lower end of the brace 25 member to a fixed support.

In the modified form shown in Figs. 6 to 11 of the drawings, the body portion of the box is constructed of wood in lieu of metallic sheets, and referring to said figures, 61 30 and 62 denote the end walls, and 63—64 the side walls. The side walls overlap the end walls as indicated at 64. The side walls are connected to the end walls by corner pieces 65 in the form of angle members, and the 35 said corner pieces are fixedly secured to the said side and end walls by bolts 66, provided with nuts 67.

Each of the side and end walls has provided in its top edge a plurality of rectangular pockets 68, and each of said walls is furthermore provided with vertically extending openings 69, which at their upper end communicate with the pockets 68 and extend to the lower edge of the wall. The 45 openings 69 are disposed centrally with respect to the pockets 68, and are cylindrical in contour.

The top 70 and bottom 71 in Figs. 6 to 11 are constructed in the same manner as the 50 top 17 and bottom 16 employed in connection with the form shown in Figs. 1 to 5, and the openings 32 in the top 70 register centrally with the top of the pocket 68, and the openings 32 in the bottom 71 register 55 with the lower ends of the openings 69.

A series of bolts are employed for connecting the bottom 71 to the side and end walls, prior to the securing of the cover in position, and each of said bolts consists of 60 an elongated tubular shank 72 provided at the lower end with peripheral threads 73, and at the upper end with peripheral threads 74. Each of the shanks 72 in proximity to

the threaded portion 74 is provided with a pair of laterally extending rectangular lugs 65 75 which are disposed in opposite directions with respect to each other and are adapted to seat in the pocket 68. The portions of the shanks of the bolts 72 above the lugs 75, are of such length as to project through the 70 cover or top 70.

The lugs 75 in connection with the nuts 76, these latter engaging the bottom 71, will fixedly secure the side and end walls to the bottom prior to the securing of the top or 75 cover in position. The lugs 75 prevent turning of the bolts when in position. Nuts 77 are mounted upon the threaded ends 74 and engage the cover or top.

The bolts 66 arranged at one end of the 80 end wall 63, and at one end of the end wall 64, are extended outwardly to receive a coupling plate 78 which is secured in position by nuts 67. The coupling plate 78 has a depending lug 79, which carries an outwardly projecting threaded bolt 80 provided with a nut for connecting the end 54 of the section 47^a of the brace member to the box. 85

From the foregoing construction and arrangement of parts it is obvious that the elements of the body portion of the case can be easily and quickly assembled and disassembled, and that when the elements of the box are disassembled they can be packed in a compact manner and can be returned to the 90 original shipper in a knocked down position at a comparatively small rate for transportation. It is also obvious that the brace members can be positioned at different angles for maintaining the case on end to prevent shifting thereof, or to prevent listing during transportation, and it is furthermore obvious that the anchoring devices can be secured to any suitable support for the purpose of maintaining the braces in position. 95 100

It is furthermore obvious that the knock-down body portion of the case can be repeatedly used for the transportation of plate glass or other kinds of merchandise, and it is furthermore obvious that the box can be 105 made of various sizes and proportions.

What I claim is:—

In combination, a plate glass shipping box adapted to be supported in shipment upon one edge, a brace pivoted at one end to the 115 end of the box adjacent the other edge of the box, and a foot piece pivoted to the other end of the brace and adapted to be secured to the body of the car in which the box is shipped. 120

In testimony whereof I affix my signature in the presence of two witnesses.

FRANK L. HAMILTON.
